United States Patent Office

Des. 193,600

Patented Sept. 11, 1962

193,600

SCARIFIER

Harvey Kravitz, 9243 Avers Ave., Skokie, Ill., and Norman Lettvin, 212 Sheridan Road, Highland Park, Ill.

Filed June 26, 1961, Ser. No. 65,719

Term of patent 14 years

(Cl. D83—12)

We claim:

The ornamental design for a scarifier, substantially as shown.
